UNITED STATES PATENT OFFICE.

RALPH H. WEST, OF CLEVELAND, OHIO, ASSIGNOR TO THE WEST STEEL CASTINGS COMPANY, OF CLEVELAND, OHIO, A CORPORATION OF OHIO.

DESIGN FOR A VEHICLE-WHEEL.

58,279.

Specification for Design. Patented June 28, 1921.

Application filed October 9, 1919. Serial No. 329,620. Term of patent 14 years.

To all whom it may concern:

Be it known that I, RALPH H. WEST, a citizen of the United States, residing at Cleveland, in the county of Cuyahoga and State of Ohio, have invented a new, original, and ornamental Design for a Vehicle-Wheel, of which the following is a specification, reference being had to the accompanying drawings, forming a part thereof.

In said drawing, Figure 1 is an elevational view of applicant's wheel; Fig. 2 is a section thereof and Fig. 3 is a section of a spoke.

I claim, The design for a vehicle wheel substantially as shown.

RALPH H. WEST.
